UNITED STATES PATENT OFFICE.

ABRAM C. MOTT, JR., OF PHILADELPHIA, PENNSYLVANIA, ASSIGNEE TO ABRAM COX
STOVE COMPANY, OF PHILADELPHIA, PENNSYLVANIA, A CORPORATION OF PENN-
SYLVANIA.

SMOKE-CONSUMING FURNACE.

1,372,534.

Specification of Letters Patent. Patented Mar. 22, 1921.

Application filed July 16, 1919. Serial No. 311,120.

To all whom it may concern:

Be it known that I, ABRAM C. MOTT, Jr., a citizen of the United States, residing in Philadelphia, Pennsylvania, have invented 5 certain Improvements in Smoke-Consuming Furnaces, of which the following is a specification.

My invention relates to certain improvements in hot water or steam boilers used 10 particularly in house heating.

One object of my invention is to provide such a boiler with a smoke consuming chamber so that the products of combustion, as they pass from the fire box, will be completely burned before entering the chimney. 15

A further object of the invention is to line the smoke consuming combustion chamber with material that will become highly heated so as to burn all of the gases passing through 20 the furnace.

A still further object of the invention is to locate the combustion chamber so that access can be readily had to the interior thereof for examination or for repairs. 25

In the accompanying drawings:—

Figure 1, is a sectional view through a steam boiler furnace of the building heating type illustrating my invention;

Fig. 2, is a sectional view on the line 2—2, 30 Fig. 1;

Fig. 3, is a sectional view on the line 3—3, Fig. 1;

Fig. 4, is a detached sectional perspective view of the casing of the combustion chamber; 35

Fig. 5, is a detached perspective view showing the heat retaining sections, which are located at one end of the combustion chamber;

Fig. 6, shows a section at the opposite end of the combustion chamber and illustrates the air passages therein; 40

Fig. 7, is a detached perspective view of the side heat retaining sections; and

Figs. 8 and 9, are detached perspective views of the top and bottom heat retaining sections, respectively. 45

Referring to the drawings, 1 is the base of the furnace. 2 is the fire chamber. 3, 3 50 are the cast iron boiler sections, each consisting of a body portion extending over the

fire chamber and having tongues 4 which extend downward as shown. At each side of each tongue are hollow projections 5 which add to the heat absorbing surface of 55 the boiler. At the rear of each boiler section is a leg 6 terminating in a mud drum 7. The upper portion of each section is recessed at each side to form flue passages 8 and 9. The sections are arranged side by 60 side, as in Fig. 2; and a series of complete flues is thus formed. These flues are connected at the front end of the boiler by vertical connecting flues 10. The sections of the boiler are coupled together by nipples 65 at the passages 11 so that the water will circulate freely through the several sections. 12 is the intake pipe for the water as it returns from the system and 13, 13 are the pipes leading from the upper portion of the 70 boiler to the system or to a manifold, according to the number of sections composing the boiler. This is a type of hot water, or steam, boiler used particularly in heating buildings. 75

At the back of the furnace structure I locate the smoke consuming combustion chamber 14. The interior of this chamber communicates with the fire chamber 2 through passages 15 at the lower portion of 80 the combustion chamber 14, and with the flues 8 through passages 16 at the upper end of the combustion chamber so that the products of combustion circulate in the fire chamber 2 and then enter the combustion 85 chamber 14 through the passages 15 and then through the passages 16 to the flues 8 and 9, and finally to the passage 17 which communicates with the flue box 18 leading to the chimney. In the roof of the combustion chamber is a passage 19 closed by a damper 20, so that when it is desired to allow the products of combustion to pass directly from the passage 14 to the chimney the damper 20 is opened. 90

21 is the casing of the combustion chamber 14 and this casing is in the form of a box having passages 15 and 16, as mentioned above, and is closed by a cover plate 22 of any suitable design and preferably made in 100 sections bolted together, as shown in Fig. 3. In order to retain a certain amount of heat

in the combustion chamber, I preferably line the casing 21 with cast iron, fire brick, or other heat retaining sections.

In Fig. 5, I have shown the sections which are located against the wall 23 of the casing. The upper and lower sections 24 and 25, respectively, are recessed, as well as the intermediate section 26 so as to form a continuation of the passages 15 and 16. The rear lining section 27 is made as shown in Fig. 6 and has ribs 28 at the back so as to form passages 29 and 29^a. 30, 30 are inclined slots communicating with the upper air passage 29, and 30^a, 30^a are straight slots communicating with the passage 29^a. The passages 29 and 29^a communicate with air openings in the casing, and back of the lining 27 is a sheet of asbestos 27^a, or other heat resisting material.

20 The side sections 31, illustrated in Fig. 7, are solid with the exception of a clean out opening 34, and the bottom section 32, Fig. 9 is also solid. The top section 33 has an opening therein forming a continuation of 25 the flue 19.

The casing 21 may be made in a single piece or in sections secured together by rivets, or other fastenings, as it will be understood that the boiler to which my invention is applied is a sectional boiler and the number of sections depends upon the area to be heated, and the casing for the combustion chamber 14 is made accordingly. Where furnaces having a given number of sections are made in large quantities, then the casings, as well as the linings, may be in single sections, if desired.

It will be seen by the above invention that the products of combustion passing from the fire chamber do not pass directly to the flue 8, as formerly, but pass into the secondary combustion chamber 14 where they come in contact with the highly heated lining of the chamber and at this point air is admitted in the proper proportion, so that the unconsumed gases will be consumed in the flues 8 and 9 before entering the chimney. I have shown air passages at the upper and lower portions of the combustion chamber. In some instances, one of these passages may be omitted, if found desirable.

I claim:—

1. The combination of a sectional steam boiler furnace having a fire chamber; boiler sections extending over the fire chamber; flues in the boiler section; a secondary combustion chamber at the rear of the furnace structure communicating at its lower end directly with the fire chamber and at its upper end with one of the flues of the boiler section, said secondary combustion chamber being lined with heat absorbing and retaining material; and means for admitting air to the secondary combustion chamber, the 65 air mixing with the products of combustion

and the waste gases being thoroughly consumed in the flues leading to the chimney.

2. The combination in a boiler furnace, of a fire chamber; a series of boiler sections mounted above the fire chamber and having 70 legs extending at the back thereof; flues in the upper portion of the boiler sections; a secondary combustion chamber located at the back of the structure and having a passage at the bottom communicating with the 75 fire chamber of the boiler; and a passage at the top communicating with one of the flues of the boiler section, the secondary combustion chamber having a lining of heat absorbing and retaining material, the rear lining 80 having an air passage therein communicating with the said secondary combustion chamber so that the products of combustion pass into the chamber from the fire box, the waste products becoming highly heated 85 and burning in the flues of the boiler before reaching the chimney.

3. The combination in a boiler furnace, of a base; a fire chamber; a series of cast iron steam boiler sections mounted above the fire 90 chamber and having legs extending at the back thereof; flues in the upper portion of the boiler section; a secondary combustion chamber at the rear of the boiler section enclosed in a casing lined with heat absorbing 95 and retaining material, and having passages leading from the fire chamber to the lower portion of the said secondary combustion chamber and from the upper portion of the said chamber to the flues in the upper portion 100 of the boiler, the combustion chamber structure being supported on the base, the lining of the chamber having an air passage communicating with the atmosphere and with the interior of the chamber so that the 105 products of combustion will become highly heated in the chamber and the unconsumed gases will be consumed in the flues of the boiler.

4. The combination in a boiler furnace, of 110 a fire chamber; a series of boiler sections connected together and mounted above the fire chamber, each section having a leg forming the rear wall of the fire chamber, said boiler sections having flues in the upper portions; a flue box; a secondary combustion chamber located at the rear of the furnace and communicating at its lower end with the fire box of the boiler and at its upper end with the flues, said secondary combustion 115 chamber having a lining of heat absorbing and retaining material, a passage communicating with the secondary combustion chamber and with the flue box; and a damper arranged to close said passage.

5. The combination in a boiler furnace, of a base, a fire chamber located above the base; a series of boiler sections supported by the base and extending longitudinally over the fire chamber and at the back thereof; flues 130

in the upper portions of the boiler sections, a secondary combustion chamber located at the rear of the boiler sections comprising a casing made in sections corresponding to the 5 sections of the boiler; and a refractory lining located within the casing and also made in sections, the rear lining having air passages therein communicating with the at-

mosphere at the lower end and at the upper end with the said combustion chamber, so 10 that the air will be heated before it enters the chamber; a cover for the said secondary combustion chamber so that on the removal of the cover the lining sections can be detached and removed, if necessary.

ABRAM C. MOTT, JR.
